UNITED STATES PATENT OFFICE.

CHARLES H. CROWELL, OF NASHUA, NEW HAMPSHIRE, AND GEORGE W. WATSON, OF SWAMPSCOTT, MASSACHUSETTS; SAID WATSON ASSIGNOR TO SAID CROWELL.

STAY-STRIP.

No. 902,563.

Specification of Letters Patent.

Patented Nov. 3, 1908.

Application filed April 18, 1907. Serial No. 368,863.

To all whom it may concern:

Be it known that we, CHARLES H. CROWELL and GEORGE W. WATSON, citizens of the United States, residing at Nashua, county of Hillsboro, State of New Hampshire, and at Swampscott, county of Essex, Commonwealth of Massachusetts, respectively, have invented a certain new and useful Improvement in Stay-Strips, of which the following is a specification, reference being had therein to the accompanying drawings.

The invention relates to a stay and binding strip which is to be folded along a straight longitudinal line in order to adapt it to be attached to two surfaces at an angle to each other.

In the making of paper boxes, in which a stay strip is used to bind together two adjoining sides of the box, the strip is usually glued or pasted partly to one of the adjoining sides and partly to the other, and therefore has to be at a right angle in order to lap over onto the two sides. Stay strips of various kinds for this purpose have been made, but difficulty has been found in bending or folding the stay strip neatly and accurately along a line parallel with the sides which is necessary in order to make a good and neat piece of work. When the stay strip is put on by machine, it is sometimes the practice to first crease the strip along the intended folding line in order to enable it to be accurately folded. Sometimes a longitudinal crease or groove is formed in the face of the stay strip. This latter method is somewhat objectionable as it weakens the stay strip along the folding line. When strips of the kind referred to are used for binding purposes, or for reinforcing, it is often times necessary that the strip should be folded in a straight line before or at the time the stay is applied.

The object of our invention is to provide a stay or binding strip so constructed that it will readily fold along the particular line desired without reducing the thickness or removing any part of the body or the adhesive along the intended folding line.

The invention consists essentially in attaching a thread or cord to the strip, preferably on the surface thereof, and along the line on which the strip is to be folded.

The invention will be fully understood from the following description taken in connection with the accompanying drawings,

and the novel features thereof will be particularly pointed out and clearly defined in the claims at the close of the specification.

In the drawings, —Figure 1 is a perspective on an enlarged scale showing a piece of stay strip embodying the invention. Fig. 2 is a perspective view showing a roll of stay strip constructed like that shown in Fig. 1 with one end partially uncoiled and attached to a corner of a box. Fig. 3 is a perspective view of a modification in which the stay strip is composed of two layers secured together by an adhesive and the thread is enclosed between the two layers.

Referring to the drawings, —A represents the stay or binding strip which for convenience in use is preferably wound into a coil B.

C represents a box to which a portion of the stay strip A shown in Fig. 2 has been applied.

The body or backing 7 of the strip is composed of cloth or paper or other suitable material such as is used for stay strips or for binding purposes or for reinforcing, and has upon one face a coating 8 of adhesive material of suitable composition which may be applied in any well known way. Secured to the gummed face of the strip is a thread or cord 9 which extends lengthwise of the strip along the line where it is intended that the strip shall be folded. This thread may be attached to the face of the strip in any suitable way, one way being by causing the thread to be laid on the strip after the adhesive has been applied and while it is still moist, so that thereby the thread will be attached to the gummed side of the strip. Any suitable and well known means whereby the thread may be laid in position on the gummed strip in proper alinement may be employed.

It is obvious that the thread may be secured to the surface of an ungummed strip or the ungummed surface of a gummed strip by applying adhesive to the thread itself or to a narrow line lengthwise of the face of the strip where the thread is to be attached, leaving the face of the strip to which the thread or cord is applied substantially free from any adhesive. The thread thus applied is equally effective to insure the even folding of the strip.

When it is desired to form the stay strip from two layers of material, as is frequently done, cloth for example forming one layer

and paper the other, the layers are usually secured together by an adhesive in a manner well known to those skilled in the art.

We contemplate the embodiment of our invention in such a compound stay strip as that which we have just referred to which is shown in Fig. 3 of the drawings, but introducing the thread or cord between the layers of which the compound strip is composed when they are being joined together. The resulting stay strip composed for example of a layer of cloth 10 and a layer of paper 11 united in the well known manner, see Fig. 3, will, when our invention is applied thereto, have a thread or cord 9 extending between them along the line on which it is desired they shall fold when employed as a stay strip binding or for similar purposes.

We find in practice that the thread attached to or contained within the stay strip as heretofore described is effective to cause the said stay strip to bend along the line of the thread when the stay strip is fed through the machine by means of which the stay is

applied to the corners of the boxes to be stayed.

We claim as our invention:

1. A stay or binding strip having a thread secured thereto along the intended folding line of the strip. 30
2. A stay or binding strip having secured to one face by adhesive material a thread extending lengthwise of the strip along the intended folding line.
3. A stay or binding strip composed of two 35 or more layers united together having between said layers a thread extending along the intended folding line.

In testimony whereof we affix our signatures, in presence of two witnesses.

CHARLES H. CROWELL.
GEORGE W. WATSON.
